RAILWAY TRAFFIC CONTROLLING
APPARATUS

John M. Pelikan, Chicago, Ill., assignor to The
Union Switch and Signal Company, Swissvale,
Pa., a corporation of Pennsylvania

Application August 26, 1942, Serial No. 456,174

6 Claims. (Cl. 246—3)

My invention relates to railway traffic controlling apparatus for governing the movement of traffic over stretches of single track through which traffic moves in both directions, and in its specific embodiment, to the provision of an improved absolute permissive block signaling system in which the signals for both directions are controlled by circuits employing but two line wires which may be energized at one end or the other by current of normal or reverse polarity to provide three position control of the signals, and in which the direction of traffic is manually governed from a central point by means of a centralized traffic control system.

My invention is an improvement upon that disclosed in an application for Letters Patent of the United States, Serial No. 412,627, filed September 27, 1941, by Henry S. Young, for Railway traffic controlling apparatus.

The object of my invention is the provision of a single track signaling system of relatively low cost employing two-wire reversible line circuits in which hand throw switches may be used in lieu of the usual power operated track switches, and in which the necessary number of track sections is reduced by the use of track circuits of the continuous code type for controlling the line circuits, the inherent efficiency and freedom from interference of track circuits of this type making it possible to use track circuits which are much longer than can be reliably operated when steady energy track circuits are used.

My invention includes the provision of novel means for the control of a block indicator for visually indicating at the control office when a train moving in either direction occupies any portion of the single track stretch, and for the control of a direction locking relay associated with the block indicator for interlocking the signal control circuits associated with the levers for the opposing head block signals governing traffic movements into the single track stretch, so as to prevent interference with train movements in the event of improper manipulation of the levers.

In accordance with this feature of my invention, the track circuits for the single track stretch, exclusive of the switch sections at the ends of the stretch, are arranged so that they all extend in the same direction, and they are normally controlled in cascade by coded current of the same frequency, such as 180 cycles per minute, to which frequency a block relay at one end of the stretch is selectively responsive. When any such track section is occupied, however, a different frequency, such as 120 cycles per minute, is supplied to the sections following the occupied section, to which frequency the block relay is non-responsive. Each such track section is provided with a code detecting relay responsive to either code frequency, which serves as a track repeating relay in place of

the usual track relay for controlling the signal circuits.

I shall describe one form of apparatus embodying my invention, and shall then point out the novel features thereof in claims.

Referring to the accompanying drawings, Figs. 1A and 1B, arranged with Fig. 1A to the left and Fig. 1B, constitute a diagrammatic view showing trackway apparatus embodying one form of my invention applied to the portion of a single track railroad located between and including the ends of two adjacent passing sidings, to which sidings access may be had by reversing the hand throw switches 1SW and 3SW, respectively. Fig. 1A also shows the control office apparatus including the signal control levers together with an illuminated track diagram of the stretch of track and associated apparatus for effecting the control and supervision of train movements over the single track block.

Similar reference characters refer to similar parts in each of the views.

In order to simplify the drawings and to enable the circuits to be more readily traced, I have herein identified each switch and signal by a number and each relay by a letter or combination of letters with a numerical prefix identifying the switch or signal with which the relay is associated. Instead of showing the sources of current for energizing all of the various circuits, I have in most instances shown only the terminals of the sources, these being identified by the reference characters B and C, referring to the power supply or positive and the common return or negative terminals, respectively.

The track plan extending across the top of the drawings represents a stretch of railway track constituting a typical single track block to which my invention is applied in the manner illustrated by the circuits below the diagram. The block extends from the head block signal 2RA or 2RB, depending upon the position of switch 1SW, to the opposing head block signal 4LA or 4LB, depending upon the position of switch 3SW, and is divided into track sections T by the usual insulated joints. Each track section T is provided with a track circuit having a current source 5 connected across the track rails at one end and a track relay TR connected across the track rails at its opposite end.

The track relays 1TR and 3TR for the relatively short detector or switch sections at the opposite ends of the block are continuously energized, while the track relays 11TR, 12TR, 13TR and 14TR for the intervening single track sections are of the code following type and the current supplied by the sources 5 for each of these sections except section 13T is periodically interrupted by the contacts of a continuously operating code transmitter 120CT or 180CT. These

code transmitters may be, for example, of the type shown in Letters Patent of the United States No. 1,858,876, granted May 17, 1932, to P. N. Bossart, for Coding apparatus, and it is to be understood that each device CT when connected to the terminals B and C of a local source of current, as shown, operates its contacts repeatedly at the rate of 120 or 180 times per minute, respectively. Sections 12T and 13T taken together constitute a "cut section," the code following relay 12TR of section 12T serving as the code transmitter for section 13T. Each of the code following relays 11TR, 13TR and 14TR have two contacts, the upper one supplying impulses of alternately opposite polarity to the primary of a decoding transformer 6, and the lower contact rectifying the code frequency impulses delivered by the secondary of the transformer 6 to operate a code detecting relay TP. The circuits for the relays TP correspond to those for the code detecting relay H in Letters Patent of the United States No. 2,237,788, granted April 8, 1941, to F. H. Nicholson et al., for Railway traffic controlling apparatus, and are arranged so that the relays TP are steadily energized in response to either 120 or 180 code operation of the associated relays TR but are nonresponsive to foreign alternating current, for reasons explained in that patent.

The track relays 13TR and 14TR also control block relays BR through the medium of decoding units 180DU connected to the corresponding decoding transformers 6. The decoding circuits are substantially similar to those shown for relay K3 in Letters Patent of the United States No. 1,773,472, granted August 19, 1930, to P. N. Bossart, for Railway traffic controlling apparatus, and include tuned circuits and rectifiers which provide a high degree of selectivity for reasons explained in the patent, so that the relays BR are steadily energized in response to 180 code operation only of the associated relays TR.

By reference to the track plan it will be seen that each of the code detecting relays TP functions like an ordinary track relay such as 1TR to indicate the condition of occupancy of the corresponding section, relay 13TP indicating the condition of the two sections 12T and 13T. Terminal B of the local source of current is connected to the transformer 6 associated with relay 14TR over a front contact of relay 3TR; consequently relay 14TP responds to the code operation of relay 14TR only when relay 3TP is picked up, and therefore indicates the condition of the two sections 14T and 3T. When relay 11TP is picked up, indicating that section 11T is unoccupied, the code frequency supplied to section 12T and consequently to section 13T, is changed from 120 to 180 cycles per minute, thereby energizing relay 13BR if these sections are unoccupied. This effects a corresponding change in the code frequency supplied to section 14T to thereby energize relay 14BR provided sections 14T and 3T are both unoccupied. The energization of relay 14BR therefore indicates that the entire block, with the exception of section 1T, is unoccupied.

The coded track circuit system thus not only serves the purpose of the usual track circuits in the control of the signals in accordance with traffic conditions, but provides in addition the equivalent of a traffic locking circuit extending substantially the full length of the block, inasmuch as it serves to indicate the presence of a train in any of the intermediate track sections of

the single track stretch or in section 3T by the deenergization of the block relay 14BR.

Inasmuch as in systems of the type shown herein only one direction of traffic can be set up at a time, intermediate signals are not required for providing head-on protection as in systems in which two head block signals may be passed at clear by opposing trains at the same time, and in the single track block chosen to illustrate my invention only two intermediate signals are provided, namely, the signals 11 and 14, constituting distant signals for the leaving signals 2L and 4R, although additional intermediate signals may readily be provided and the single track block may also include a greater or lesser number of track sections, depending upon traffic requirements and upon the distance between the passing sidings.

The territory illustrated may be extended through either passing siding to the entrance to an adjacent single track block, merely by placing Fig. 1A at the right of Fig. 1B. When so arranged, the track plan illustrates the opposite ends of a block extending from signal 4R to the right through track sections 3T and 1T to an opposing signal such as signal 2L, but located in the next single track block to the right of that described above, but since the circuits for controlling the opposing signals 4R and 2L form no part of the present invention they have not been shown herein, suitable circuits being well known. For example, these signals may be controlled by circuits similar to those for signals R2 and L4 shown in Letters Patent of the United States No. 2,282,841, granted May 12, 1942 to H. S. Young, for Railway traffic controlling apparatus.

It will be understood that each of the head block signals is controlled automatically by the track relays in accordance with traffic conditions in advance, and is also subject to manual control from the central office illustrated in Fig. 1A, through the medium of a centralized traffic control system.

The communication system connecting the office with the various field locations may be of any suitable type, and as shown herein it is to be understood to be of the impulse code type such as that shown in Letters Patent of the United States No. 2,229,249, granted January 21, 1941, to Lloyd V. Lewis, for Remote control systems. In this system, communication is established intermittently between the control office and various field stations over a single pair of line wires extending from the office through each station corresponding to the location of a head block signal such as those shown in Figs. 1A and 1B of the present disclosure, in the manner illustrated in Fig. 10 of the Lewis patent. Direct wire control may also be used, and as illustrative of either form, those communication channels of the impulse code system which are directly involved in the operation of the apparatus of my invention are shown herein as direct wire connections extending from the office to the two field stations at the opposite ends of the block. These include the control channels over which signal control relays 2RHS and 4LHS are energized in response to movement of the signal levers 2SG and 4SG to the right and left, respectively, to establish the corresponding traffic direction and to effect the clearing of the respective head block signals 2RA and 4LA. They also include two indication channels over which the track indication relays 1TK and 3TK are energized to indicate the occupancy of the respective switch sections

1T and 3T; two channels over which the signal indication relays 2RHK and 4LHK are energized in response to the release of relays 2RGP and 4LGP, respectively, the latter relay being released when the corresponding signals are cleared, and they also include a channel over which a block indication relay BK is picked up in response to the release of relay 14BR, indicating the occupancy of the main portion of the single track block, exclusive of section 1T. The office apparatus also includes a direction locking relay 2-4LP, of the stick polar type, as in the system of the above-mentioned Young patent, and a normally energized indication storing stick relay 1TKS governed jointly by relays 1TK and BK.

The signal circuits are of the two wire reversible line circuit type corresponding generally to those disclosed in Letters Patent of the United States No. 2,112,945, granted April 5, 1938, to L. B. Yarbrough, for Railway traffic controlling apparatus. That is to say, the signals for both directions are controlled over a system of cascade connected line circuits energized at one end or the other in accordance with the traffic direction established by the manually governed relays 2RHS and 4LHS. Thus signal 2RA is governed by a line relay 2RHR, which is controlled at times by a relay 12HR, at the location of signal 11, over a circuit including the line wires 25 and 26 and front contacts of relays 1TR and 11TP reflecting the condition of track sections 1T and 11T. This line circuit serves at other times for the control of the mechanism 11G of signal 11. Relay 12HR, in turn, is controlled at times by relay 14HP, at the location of signal 14, over a circuit including line wires 31 and 32, and contacts of relay 13TP which reflect the condition of track sections 12T and 13T, the same line wires providing a circuit at other times over which relay 11HP, governed by mechanism 11G, controls the line relay 13HR. Relay 14HP is governed by the mechanism 14G for signal 14, which in turn is controlled at times over line wires 27 and 28 and contacts of relay 14TP reflecting the condition of track sections 14T and 3T, the same line wires providing a circuit at other times over which relay 13HR, at the location of signal 14, controls the line relay 4LHR which governs signal 4LA. The directional control, as shown, is arranged as in the corresponding circuits of the above-mentioned Young application by the provision of the traffic direction relays 2RFR and 4LFR and the directional stick relays 2RFS and 4LFS for controlling the direction of energization of the cascade connected line circuits in place of direct control by the code controlled relays 2RHS and 4LHS, as employed by Yarbrough. The control effected by these directional relays is such that as soon as the establishment of either traffic direction is completed by the energization of the line relay 2RHR at one end or of relay 4LHR at the other end, the code controlled relay 2RHS or 4LHS at the entrance end is free to be picked up or released as required to control the adjacent signal without interrupting the continuity of the line circuit, and the established traffic direction is maintained by keeping the code controlled relay 4LHS or 2RHS at the exit end deenergized. Furthermore, slow acting polarized line relays HR take the place of the signal mechanisms G in the circuits at locations where the intermediate signals are omitted, and also at the ends of the block where they control the head block signals. Each intermediate signal mechanism is provided with the usual slow acting

repeating relay HP and a directional stick relay S for setting up the circuits for permissive following train movements. Relay 11S is controlled by the adjacent track repeating relay 11TP in the usual manner, but no such relay is available at the location of relay 14S, and for the control of that relay a "floating" track relay 14ATR of the code following type is connected across the track rails at the battery end of section 14T. Relay 14ATR responds periodically to the coded current from the associated source 5 and holds a slow acting repeating relay 14ATP picked up, relay 14ATP releasing when a train passes signal 14 to effect the directional energization of relay 14S in the usual manner.

The line circuits as shown are in the condition in which they are left following a train movement from left to right through the block. The directional relay 4LFR is energized over back contacts 5 7, 8 and 9 of relays 4LHS, 4LFS and 4LHR, and connects terminals B and C to the adjacent line circuit at the right-hand end, over contacts of a pole changer relay 4R-PC and an approach locking relay 4LAS, which function like the corresponding relays shown in Yarbrough, and the circuit is completed over line wires 27 and 28 through mechanism 14G over front contacts of relays 4LFR and 14TP, and back contacts of relay 13HR. Relay 4R-PC is deenergized, signal 4R being at stop, and consequently mechanism 14G is energized in the reverse direction to cause signal 14 to indicate caution, and to energize relay 14HP, the latter relay connecting terminals B and C to the right-hand end of the circuit comprising the next section of the line circuit system, which circuit is completed through relay 12HR over front contacts of relay 13TP, line wires 31 and 32 and back contacts of relays 11HP and 11S. Relay 12HR is energized in the normal direction and completes a circuit comprising the third section of the line circuit system through relay 2RHR over the normal polar and neutral front contacts of relay 12HR, line wires 25 and 26, front contacts of relays 11TP and 1TR, and back contacts of relay 2RFR. Relay 2RHR is therefore energized in the normal direction and holds the circuit for relay 2RFR open at contact 10. The circuits for controlling signal 2RA, shown only in part, include front contacts 41 and 42 of relays 2RHS and 2RFR and are now open at contact 41. The circuits for controlling signal 2RB are also open, it being understood that these include contacts 41 and 42 and also other contacts, not shown, which are closed only when switch 1SW has been reversed by the train crew. I shall now assume that the apparatus is in the condition shown and that the operator moves levers 2SG and 4SG to the right, with the object of clearing signals 2RA, 14 and 4R for a train movement through the block from left to right. Relay 2RHS will become energized upon the delivery by the communication system of the proper code in response to the closing of the circuit including right-hand contact 43 of lever 2SG and left-hand contact 44 of the direction locking relay 2-4LP. The energization of relay 2RHS completes the circuit for signal 2RA, which signal will therefore clear, thereby releasing relay 2RGP to energize the office indication relay 2RHK, the latter relay, it will be understood, controlling a suitable indication lamp, not shown. It will also be understood that signal 4R will be caused to indicate caution or clear in response to the movement of lever 4R to the right,

so that relay 4R-PC will be picked up and signal 14 will indicate proceed.

The energization of relay 2RHK locks relay 2-4LP normal by opening contact 15 in its reverse energizing circuit which includes left-hand contact 16 of lever 4SG. Signal 2RA now cannot be put to stop by the operation of any lever other than its control lever 2SG, as, for example, by a movement of lever 4SG to the left, nor can the intermediate signal 14 now be put to stop by a movement of lever 4SG to the left. The line circuit system comprising the circuits for controlling signals 2RA and 14 is completed over front contacts of relay 4LFR, which relay is held energized over back contact 7 of relay 4LHS, and relay 4LHS is held released because its circuit, which includes wire 33 and left-hand contact 17 of lever 4SG, is open at contact 44 in its normal position, and relay 2-4LP is non-responsive to a movement of lever 4SG to the left due to the fact that contact 15 is open.

When the train governed by signal 2RA enters the first track section 1T of the block, relay 1TR releases, opening the line circuit to release relay 2RHR, thereby putting signal 2RA to stop and consequently reenergizing relay 2RGP.

The dropping of relay 1TR before the slow acting relay 2RHR releases completes a pick-up circuit at contact 47 for the directional stick relay 2RFS, which relay picks up and is held energized after relay 2RHR releases, over a stick circuit including back contact 18 of relay 2RHR, opening contact 19 in the circuit for relay 2RFR before contact 10 of relay RHR closes.

At the office, relay 1TK picks up to light the "OS" lamp 1E and the block indication lamp BE in response to the release of relay 1TR, and relay 2RHK becomes deenergized in response to the reenergization of relay 2RGP. Relay 2RHK is made slow to release so that when relay 1TK picks up, terminal B is disconnected from the stick circuit for relay 1TKS for a time sufficient to effect the release of relay 1TKS, and when relay 1TKS releases, a second circuit for the block indication lamp BE, over back contacts of relays 2RHK and 1TKS is completed. It will be seen that the circuit for reversing relay 2-4LP is now open at contacts 20 and 21 of relays 1TK and 1TKS so that the direction locking is still effective.

When the advancing train enters section 1T the code operation of relay 1TR ceases, releasing relay 1TP, and the dropping of contact 22 of relay 1TP causes 120 code to be supplied to section 1T. This 120 code is repeated by relay 12TR, and supplied from the associated source 5 over wires 34 and 35 to the track rails of section 1T with the result that relay 13TR is operated at the 120 code rate to maintain relay 13TP energized, but relay 13BR releases to cause 120 code to be supplied to section 1T. Relay 14BR therefore releases to pick up the office relay BK over wire 36 thereby indicating the presence of the train in that portion of the stretch which is at the right of section 1T. Relay BK maintains lamp BE lighted, and by opening back contact 23 holds relay 2-4LP locked normal until the train vacates the last track section 3T of the block.

The indication codes transmitted by the communication system for controlling relays 1TK and BK are transmitted from different stations, and if this system is of the impulse code type, they are not only transmitted at different times but the delivery of one or the other may be delayed due to the use of the communication line

circuit by other stations, and it may happen that if a train governed by signal 2RA passes the corresponding station and occupies section 1T for a relatively short time, a second code will be received at the office from that station to announce the departure of the train from section 1T, thereby releasing relay 1TK, before the indication is received from the station at the exit end of the block announcing the movement of the train into section 1T. Relay 1TKS serves as an indication storing relay to maintain the block indication and direction locking during this interval, that is, if it should happen that relays 1TK and BK are both released while there is a train in the block. Relay 1TKS releases when the train first enters section 1T, as already explained, and is picked up by relay BK in response to the receipt of the indication from the second station that the train has entered another portion of the stretch, upon the closing of front contact 23.

As the train passes signal 14, the track relays 14ATR and 14TR will be shunted, stopping their code operation so that relay 14ATP will release to pick up the directional stick relay 14S, and then mechanism 14G and relay 14HP will release in response to the release of relay 14TP by relay 14TR, relay 14HP completing the usual stick circuit to hold relay 14S energized. When the train vacates section 1T, relay 12HR will become energized in the reverse direction over the front contacts of relay 14S, and in turn will cause relay 2RHR to become energized in the reverse direction, causing signal 2RA to indicate caution, provided relay 2RHS is still energized. Relay 2RHR releases relay 2RFS, closing back contact 19 after contact 10 opens, so that relay 2RFR is held released and cannot be picked up by releasing relay 2RHS.

When the train enters section 3T, relay 3TR releases, energizing the office indication relay 3TK over wire 37, and consequently the "OS" lamp 3TE becomes lighted. When the train vacates section 1T, the code operation of relay 14TR will be resumed, and when it vacates section 3T, relay 3TR picks up to release relay 3TK and thereby extinguish lamp 3TE, and to supply current to the decoding transformer 6 associated with relay 14TR, whereupon relays 14BR and 14TP pick up. Relay 14TP restores the line circuits to the condition shown in the drawings, and relay 14BR releases relay BK, extinguishing lamp BE and rendering relay 2-4LP again responsive to signal lever operation.

I shall next assume that the apparatus is in the condition shown and that the operator moves levers 2SG and 4SG to the left, with the object of clearing signals 4LA, 11 and 2L for a train movement through the block from right to left.

The movement of lever 4SG to the left completes the reverse energizing circuit for relay 2-4LP at contact 16, whereupon relay 2-4LP operates its contact 44 to the right, completing a circuit at contacts 44 and 17 over wire 33 to pick up relay 4LHS. Relay 4LHS, by opening contact 1 releases relay 4LFS, deenergizing the line circuit system and connecting relay 4LHR thereto at its right-hand end. Mechanism 14G, and relays 14HP, 12HR and 2RHR release, and relay 2RFR picks up over back contacts 10, 41 and 19 of relays 2RHR, 2RHS and 2RFS and connects terminals B and C to the left-hand end of the line circuit system over contacts of relays 2L-PC and 2RAS. Mechanism 11G, and relays 11HP, 13HR and 4LHR then become energized successively, relay 4LHR opening contact 9 in the circuit

for relay 4LFR and completing the circuit for clearing signal 4LA. It will be understood that signal 2L will be caused to indicate caution or clear in response to the movement of lever 2SG to the left, and that consequently signal 11 will indicate proceed. The clearing of signal 4LA releases relay 4LGP, initiating an indication code to pick up the office indication relay 4LHK over wire 38, thereby opening back contact 24 to lock relay 2-4LP reversed. Signals 4LA and 11 now cannot be put to stop by a movement of lever 2SG to the right, relay 2RFR being held energized over back contact 41 of relay 2RHS, the circuit for which is open at contact 44 in its reverse position. Relay 2-4LP now does not respond to a movement of lever 2SG to the right because its normal energizing circuit is open at contact 24.

When the train governed by signal 4LA enters the first track section of the block, in this case section 3T, relay 3TR releases, deenergizing transformer 6 associated with relay 14TR to cause the release of relays 14BK and 14TP. Relay 14TP opens the line circuit to release relay 4LHR, thereby putting signal 4LA to stop and consequently reenergizing relay 2RGP.

The dropping of relay 3TR before relay 4LHR releases completes a pick-up circuit for relay 4LFS, which relay picks up and is held energized over its stick circuit to maintain relay 4LFR released by opening contact 8 before contact 9 closes.

The release of relay 3TR also initiates an indication code, energizing relay 3TK over wire 31 to light the "OS" lamp 3E, also releasing relay 4LHK and energizing relay BK, thereby lighting lamp BE and opening contact 23 in the circuit for relay 2-4LP before contact 24 closes. In this instance it is obvious that since the block indication is transmitted in the first code along with the "OS" indication the operation of a storing relay such as the relay 1TKS above described is not required, that relay being held energized over a back contact of relay 2RHK.

As the advancing train passes through the block, the successive release of the track repeating relays TP and of relay 1TR controls the signal circuits in a manner similar to that already described. Lamp 1E will become lighted by the energization of relay 1TK in response to the "OS" indication code announcing the movement of the train into section 1T, lamp BE remaining lighted and the direction locking remaining effective until codes are received from both stations, to release relays 1TK and BK, respectively.

It will be clear from the foregoing that the operator is able to send codes at will for energizing relay 2RHS or 4LHS to effect the clearing of the associated head block signal 2RA or 4LA for a train movement in the direction of traffic already set up, but that to reverse the direction of traffic, the block indicator must indicate that the block is unoccupied in response to indications received from the two stations at opposite ends of the block, and the lever locking relay 2-4LP must be operated in the required direction prior to the transmission of the code for clearing the signals. It follows that the signals which have been cleared cannot be interfered with by an inadvertent attempt to clear an opposing signal.

Although I have herein shown and described only one form of railway traffic controlling apparatus embodying my invention, it is understood that various changes and modifications may be made therein within the scope of the appended

claims without departing from the spirit and scope of my invention.

Having thus described my invention, what I claim is:

5. In a block signaling system for railways, a stretch of track divided into track sections, a track circuit for each track section having a track relay, head block signals for governing traffic movements into the stretch in opposite directions, a manually controlled relay for each signal, a system of cascade connected line circuits for controlling the signals, each line circuit extending the length of one or more track sections and including contacts controlled by the track relays which are closed only when the corresponding track sections are unoccupied, means controlled by back contacts of each manually controlled relay for supplying current to the adjacent end of the line circuit system to effect the energization of said line circuits in cascade to thereby prepare a circuit for the opposing signal at the other end of the stretch, means comprising front contacts of each manually controlled relay for controlling the associated signal in accordance with the condition of energization of said line circuit system when supplied with current at its opposite end, a block relay near one end of the stretch, means including the track relays for connecting said track circuits in cascade and for transmitting distinctive currents over the track rails section by section to the location of said block relay only when all the block sections are unoccupied, means controlled by the track relays and selectively responsive to said distinctive currents for energizing said block relay, direction locking means effective when in one condition to prevent the energization of one manually controlled relay and when in another condition to prevent the energization of the other manually controlled relay, and means preventing a change in the condition of said direction locking means except when said block relay is energized.
2. In a block signaling system for railways, a stretch of track divided into track sections, a track circuit for each track section having a track relay and a source of current, a code transmitter for each track circuit for periodically interrupting the current supplied thereto at a predetermined rate, a code detecting relay for each section which assumes its energized position in response to the periodic operation of the associated track relay, head block signals for governing traffic movements into the stretch in opposite directions, a manually controlled relay for each signal, a system of cascade connected line circuits extending the length of the stretch for controlling the signals said line circuits including front contacts of the code detecting relays for the adjacent track sections, means controlled by back contacts of each manually controlled relay for supplying current to the adjacent end of the line circuit system to effect the cascade energization of a plurality of said line circuits to thereby prepare a circuit for the opposing signal at the other end of the stretch, means comprising front contacts of each manually controlled relay for controlling the associated signal in accordance with the condition of energization of said line circuit system when supplied with current at its opposite end, a block relay near one end of the stretch responsive to the periodic operation of the adjacent track relay at a rate different from said predetermined rate, means effective when the code detecting relay for a track section near the

other end of the stretch is energized for periodically interrupting the current supplied to the remaining track circuits section by section in cascade at a rate to which said block relay is responsive to effect the energization thereof only in the event all of said track sections are unoccupied, direction locking means effective when in one condition to prevent the energization of one manually controlled relay and when in another condition to prevent the energization of the other manually controlled relay, and means preventing a change in the condition of said direction locking means except when said block relay is energized.

3. In a block signaling system for railways, a stretch of track divided into track sections, a track circuit for each track section having a track relay, head block signals for governing traffic movements into the stretch in opposite directions, a system of cascade connected line circuits for controlling said signals, said line circuits including contacts controlled by the adjacent track relays which are closed when the corresponding track sections are unoccupied, means at each end of the block for supplying current to the line circuit system at that end to effect the energization of said line circuits in cascade to thereby prepare a circuit for the head block signal at the other end of the stretch, means for completing said prepared circuit to effect the clearing of such head block signal when all the track sections are unoccupied, and also when one or more of the track sections are occupied by a train moving in the direction governed by such signal to permit a following train to enter the stretch, a block relay near one end of the stretch, means controlled by the track relays for energizing said track circuits in cascade and for transmitting distinctive currents over the track rails section by section to the location of said block relay only when all the track sections are occupied, means selectively responsive to said distinctive currents for energizing said block relay, and a visual indicator for indicating the presence of a train in the stretch located at a central office and controlled by said block relay.

4. In an absolute permissive block signal system, a stretch of railway track divided into block sections and provided with coded track circuits a plurality of which are arranged to be controlled in cascade, a code detecting relay at one end of each such track circuit responsive to coded current supplied to the other end thereof, a line circuit system extending from the entrance to the exit end of said stretch including a line circuit corresponding to each block section each said line circuit including front contacts of the code detecting relay or relays responsive to the condition of the corresponding portion of track, a three position signal for governing the movement of traffic into each block section in a given direction, an electroresponsive device for controlling each signal adapted to be energized over the line circuit for the block section in advance thereof, means at the exit end of the stretch for supplying current of normal or reverse polarity to the line circuit which extends to that end of the stretch, means at each intermediate signal location for supplying current of normal relative polarity to the line circuit extending to the rear thereof only when the electroresponsive device at that location is energized, and for supplying cur-

rent of reverse relative polarity to that line circuit only when such electroresponsive device is deenergized by a train in the corresponding block section moving in said given direction, manually

5 operable means at a control office for at times disconnecting the supply of current of normal or reverse relative polarity from the line circuit near the exit end of the stretch, a block relay at one end of the stretch, means for constantly supplying coded current to that one of said track circuits which is nearest the other end of the stretch, means dependent upon the energized or deenergized condition of the code detecting relay for said one track circuit for supplying coded current of one frequency or another, to which the code detecting relays are responsive, to each remaining track circuit in said stretch, cascade means effective only when coded current of said one frequency is received over the track circuit 10 nearest said one end of the stretch for energizing said block relay, and means at said office remotely controlled by said block relay for preventing the disconnection of said source of current from the line circuit at the exit end of the stretch unless the block relay is energized.

25 5. Traffic locking means for a stretch of single track over which traffic may move in either direction comprising, in combination, a detector track circuit at each end of the stretch having a track 30 relay, a block relay at one end of the stretch, means for transmitting current over the track rails of the intervening portion of said stretch to energize said block relay, said means being effective only when the track relay adjacent said 35 block relay is picked up, two indication relays located at a central office, means for controlling one indication relay to indicate the condition of said block relay, means for controlling the other indication relay to indicate the condition of the 40 track relay at the other end of the stretch, direction locking means at said office for governing the direction of traffic movements into said stretch, and circuits controlled jointly by the two indication relays for controlling said direction 45 locking means to prevent the reversal of traffic direction except when the entire stretch is unoccupied.

50 6. In a centralized traffic control system, an office and two stations, a stretch of single track extending between said stations, a detector track circuit at each end of the stretch having a track relay at the adjacent station, a block relay at one station, means for transmitting rail currents over the portion of track included between said 55 detector sections to energize said block relay but only if the track relay at said one station is energized, a block indication relay at said office controlled by the block relay, two track indication relays at the office one controlled by each 60 track relay, a track diagram representing said stretch of track having track indication lamps for illuminating the detector track portions at the ends of the stretch and a block indication lamp for illuminating the intervening track, a circuit 65 controlled by each track indication relay for energizing the associated track indication lamp when the corresponding detector section is occupied, and circuits controlled by the block indication relay and one track indication relay for energizing the block indication lamp when any portion of the stretch is occupied.

JOHN M. PELIKAN.

CERTIFICATE OF CORRECTION.

Patent No. 2,354,052.

July 18, 1944.

JOHN M. PELIKAN.

It is hereby certified that error appears in the printed specification of the above numbered patent requiring correction as follows: Page 6, second column, lines 17 and 18, claim 4, for "stretch, cascade means" read --stretch, in cascade, means--; and that the said Letters Patent should be read with this correction therein that the same may conform to the record of the case in the Patent Office.

Signed and sealed this 5th day of September, A. D. 1944.

Leslie Frazer
